UNITED STATES PATENT OFFICE.

LEOPOLD C. SCHMIDT, OF JERSEY CITY, NEW JERSEY.

GARMENT-FORM.

No. 799,195.

Specification of Letters Patent.

Patented Sept. 12, 1905.

Application filed October 31, 1904. Serial No. 230,636.

To all whom it may concern:

Be it known that I, LEOPOLD CONSTANTINE SCHMIDT, a resident of Jersey City, Hudson county, State of New Jersey, have invented 5 certain new and useful Improvements in Garment-Forms, of which the following is a specification.

My invention relates to garment-forms or display-figures, and has for its object to provide an improved device of this character wherein the head portion is detachable from the body portion, so that the same may be used for different display and the body be used with a variety of heads.

15 To these and other ends, which will hereinafter appear, the invention consists in the novel features of improvement and combination and arrangement of parts which will be hereinafter set forth, and finally summarized 20 in the appended claims.

In the accompanying drawings, forming part 25 of this specification, Figure 1 represents a side elevation, partly in section, of a garment-form embodying my invention. Fig. 2 is a rear view thereof. Fig. 3 is a plan view of the body portion of the garment-form on a reduced scale. Fig. 4 is a bottom plan view 30 of the head portion of the garment-form, also on a reduced scale, the shape of the base in this instance being of somewhat different 35 form; and Fig. 5 is a perspective view of the base portion of the head of the garment-form, on a reduced scale, the shape of the base in this instance being also of a different form.

Like numerals of reference indicate corresponding parts in the several views.

Referring to the drawings, the numeral 1 indicates the body portion of the garment-form, the upper part of which is provided with an 40 inclined tapered recess or channel 2, the sides 3 of said recess being, by preference, angularly disposed and gradually converging toward each other to the front of the body, as shown in Fig. 3. The head portion 4 is provided with a tapering base 4^a, which is adapted 45 to snugly fit within the recess 2 of the body 1, the sides 5 of the base 4^a being, by preference, angularly disposed to match the sides 3 of the recess 2, whereby the head portion of the garment-form can be readily slipped into position 50 upon the body portion and firmly held thereon. When in position, the end 6 of the base 4^a will be flush with the outer surface of the garment-form body. (See Fig. 1.) In order to secure the head portion and body 55 portion of the garment-form more firmly

yet detachably together, I provide the body 1 within the recess 2 with a block 10, secured to the shelf 7, which block acts as a key and stop within the slot 13 of a spanner 12, provided in the base of the head portion, as shown in Figs. 1 and 4.

8 indicates a bolt or the like passing through the block 10 and shelf 7 and which has mounted upon it a wing 9, and between the wing and 60 block 10 is a spring 11, adapted to keep the wing up, the opposite end of the bolt below the shelf 7 being screw-threaded and receiving a nut 9^a.

In order to get at the wing 9 when the head 70 and body are assembled to turn the same into locking-position, I provide the head portion 4 at a point which corresponds to the back of the neck with an opening 14, through which the fingers of the operator can be inserted. In order to facilitate the withdrawal 75 of the head portion from the assembled position, I provide at the base thereof a piece of felt or the like 15, which can be readily gripped without soiling the wax of which the head- 80 pieces are usually constructed.

To secure the body and head portions together, the base 4^a of the head portion is pushed or slid into the recess 2, with the wing 9 and bolt 8 projecting through the slot 13, 85 the wing 9 being designed to pass through the slot when turned parallel with the same. Having done this the operator inserts his fingers within the opening 14 and turns the wing until it firmly presses against the spanner 12. (See Fig. 1.) To disassemble the parts, this operation is reversed. The block 10 within the slot 13 when the head portion is in position upon the body portion acts as a stop or abutment, as will be seen from Figs. 90 1 and 3, preventing the head portion from slipping out of its proper position upon the body.

The head portion of the garment-form hereinabove described is preferably a wax figure, 100 with a suitable framework and base of wood or other material, and the body portion 1 is by preference constructed of papier-mâché or the like upon a suitable framework of well-known construction.

Having now described my invention, what I claim, and desire to secure by Letters Patent, is--

1. A garment-form, comprising a body portion having an inclined channel at the top, and 110 a head portion adapted to fit in the inclined channel, the base of the head portion having

a slot, and the inclined channel being provided with a block adapted to enter the slot.

2. In a garment-form, a body portion and a detachable head portion, the body portion being provided with an inclined tapered recess adapted to receive the base of the head portion, and means for holding the head and body portions together.

3. A garment-form comprising a body portion and a detachable head portion, the body portion being provided with a tapering recess or channel, and the head portion being provided with a tapering base adapted to fit within said recess, and means for locking the head and body portions together.

4. A garment-form, comprising a body, a detachable head portion, the body being provided with a tapering recess at the top, and the head portion having a tapering base adapted to fit within said recess, the base of the head portion being provided with a slot, a bolt adapted to pass through said slot, a nut carried by the bolt, a wing also carried by the bolt, and a spring upon the bolt adapted to

bear upon the wing, all substantially as and for the purpose described.

5. A garment-form comprising a body portion, having an inclined channel at the top, the side walls whereof converge toward each other, and a head portion adapted to be detachably secured to the said body portion, the head portion having an inclined base adapted to snugly fit in said channel, substantially as described.

6. A garment-form comprising a body portion having an inclined channel at the top with side walls converging toward the front, a stud rising from the base of the channel, and a head portion adapted to be detachably secured to the body portion, the base of the head portion fitting in said channel and provided with a slot adapted to receive said stud, substantially as described.

LEOPOLD C. SCHMIDT.
